UNITED STATES PATENT OFFICE.

EDWIN NAPIER STEPHENSON, OF PHILADELPHIA, PENNSYLVANIA, ASSIGNOR TO ELLIOTT-FISHER COMPANY, OF HARRISBURG, PENNSYLVANIA, A CORPORATION OF DELAWARE.

PLATEN EQUIPMENT FOR TYPE-WRITING MACHINES.

1,128,382.

Specification of Letters Patent.

Patented Feb. 16, 1915.

Application filed June 3, 1912. Serial No. 701,437.

To all whom it may concern.

Be it known that I, EDWIN N. STEPHENSON, a citizen of the United States of America, residing at Philadelphia, in the county 5 of Philadelphia and State of Pennsylvania, have invented certain new and useful Improvements in Platen Equipment for Type-Writing Machines, of which the following is a specification.

10 This invention relates to the platen equipment of typewriting machines and more particularly to the equipment of the platen of a flat platen typewriter with instrumentalities designed to facilitate certain classes 15 of billing as, for instance, telephone billing, so called.

The structure here shown is designed for use in connection with an elaborate system devised by me to facilitate ledger posting, 20 toll billing and many other operations too numerous to mention, but which contribute to the general object of caring for the recording and billing in telephone and other accounting offices.

25 Generally speaking, one object sought to be obtained is the production of an efficient arrangement facilitating manifold work in connection with a set of work elements, one or more of which are of the kind known as 30 folded forms.

To this end the invention consists in equipping the platen with an endless transfer web combined with tension and feeding mechanisms, work-holding and guiding 35 tapes and means for automatically elevating the web, the whole being combined in a manner to facilitate the displacement and replacement of the work elements and their retention in accurate position for recording.

40 Another object of the invention is to equip the platen with work clamping and gaging devices associated with means for effecting both the automatic and manual operation thereof under varying conditions of use and 45 adapted to be rearranged for use in connection with different classes of work.

Another object of the invention is to equip the platen with a group of work gages and machine stops adapted to retain the work 50 elements in progressive positions and to arrest the traveling machine in corresponding progressive positions appropriated to different billing or recording periods.

Other objects of the invention subordinate

to those enumerated will appear as the succeeding description of the illustrated embodiment of the invention is developed.

In the accompanying drawings—Figure 1 is a perspective view of a platen equipped in accordance with my invention and showing the typewriting machine supported by the tracks in normal position, the structure being viewed from the rear. Fig. 2 is a plan view of the platen with the parts arranged for ledger posting or billing and statement work. Fig. 3 is a perspective view of the under side of the platen and its equipment. Fig. 4 is a longitudinal sectional view on the line 4—4 of Fig. 3. Fig. 5 is a similar view on the line 5—5 of Fig. 70 3. Fig. 6 is a section partly in elevation of the rear end of the platen. Fig. 7 is a diagrammatic view showing the relation of the ribbon and platen when the ribbon is elevated by the raising of the track frame. 75 Fig. 8 is a perspective view designed more particularly to show the work gaging and clamping plates and the mechanism contributing to the operation and control thereof. Fig. 9 is a detail view of the clutch 96 and 80 its associated parts with the clutch disengaged to permit the manual manipulation of the work gaging and clamping plates when the cam lever is held depressed by the machine. Fig. 10 is a detail sectional view 85 designed more particularly to show the manner in which the toll bill clamp and the longitudinal gage clamp may be interchangeably employed. Fig. 11 is a detail view of the clutch-operating handle and its 90 detent. Fig. 12 is a longitudinal section of the shaft 92 and associated parts. Fig. 13 is a detail perspective view of the rails of the track frame, the main ribbon roller and the mechanisms for locking, releasing and 95 raising the rails and for operating the ribbon roller to feed the ribbon. Fig. 14 is a detail view of the lever 68 and its mounting. Fig. 15 is a detail sectional view of the push rod 48. Fig. 16 is a detail view 100 of one part of the automatic device for releasing the track frame and feeding the ribbon. Fig. 17 is a perspective view of the platen with the machine head removed. Fig. 18 is a detail sectional view of the front 105 end of the track frame. Fig. 19 is a detail side elevation of the spring drum shown in Fig. 18. Figs. 20 and 21 are detail views

showing the manner of mounting the guide roller 16 in the track frame. Fig. 22 is a detail view showing the manner of attaching the tape 26 to the cross bar 5. Fig. 23 5 is a detail view of the cam depressing roller which is used for toll billing. Fig. 24 is a sectional view showing the manner of operating the stop carrying bars 75. Fig. 25 is a horizontal section of the same mechanism. 10 Fig. 26 is a detail perspective of the clamp for use in place of the gage plate 90 when it is desired to do toll billing.

By way of premise it may be stated that the structure hereinafter described is designed with special reference to the equipment of a flat platen typewriter, the example shown being the well known Elliott Fisher billing machine of commerce which, as is well understood in the art, includes in 15 addition to the flat platen, a machine frame *a* which travels longitudinally of the platen on tracks or guides to effect line spacing and a carriage *b* which travels on the machine frame *a* transversely of the platen to letter 20 space the writing effected by downwardly acting printing mechanism which is mounted on and moves with the carriage. This general organization is fully shown in Fig. 25 1 of the accompanying drawings and the 30 succeeding description will presuppose familiarity with the construction and usual operation of this well known type of machine.

A flat platen 1 is partially covered by the 35 usual hard rubber or other suitable writing surface 2 and has extended thereover tracks or guides 3 and 4, having fixed rear sections 4^a, and swinging front sections 4^b, the latter being connected at their front ends by 40 the usual front bar 5. In front brackets 6, depending from the tracks is journaled a swinging tension frame 6^a, comprising a pair of side arms 7, between the ends of which are extended a pair of guide rollers 45 8 and 9. One end of the tension frame is journaled on a short spring urged trunnion 10, having an enlarged head 11, by means of which the trunnion may be pulled out to release the tension frame. The other end of 50 the tension frame is fitted upon the pyramidal end of a short shaft 12, journaled in one of the front brackets and passed through the casing of the spring drum 13. Within this drum is a tension spring 13^a for the 55 tension frame. This spring is connected to the shaft and drum respectively and to the bracket 6 is rigidly secured a ratchet 14, engaged by a pawl 14^a, pivoted on the drum casing. The swinging tension frame 6^a is 60 closed within the front end or loop of an endless transfer web or ribbon 15, the upper and lower runs of which lie closely imposed one upon the other when the track frame is in its normal depressed position. 65 (See Fig. 4). In this position both the up-

per and lower guide rods of the tension frame are located below the plane of the writing surface, the tension frame being swung rearward by the pull on the ribbon incident to the angular form assumed by the 70 ribbon in passing from the front end of the platen to the rollers of the tension frame. When the track frame is elevated the upper and lower runs of the ribbon are allowed to separate as the tension frame rises, but the 75 tension on the ribbon is maintained by the forward or outward swinging of the tension frame under the action of the spring 13^a. In rear of the tension frame the upper run of the ribbon is supported and guided by a 80 guide roller 16 journaled in the upper rear corners of the front brackets. The lower run of the ribbon, when depressed, is guided by a guide roller 17, forming the upper front corner of the platen. Beyond the rear end 85 of the platen rear brackets 18 are dropped from the tracks and connected by a rear bar 19. Journaled in these brackets are two 90 guide bars 20, 21, over which the runs of the ribbon pass to the main ribbon roller 22, carried at the left hand side of the platen by a snap trunnion extended through one of the rear brackets 18. To the other end of the 95 roller is secured a shaft 23 extended through the other bracket 18 and provided at the outer side thereof with a ratchet wheel 23^a engaged by a ribbon feed pawl 24, carried by a feed lever 25 journaled on the shaft 23 and retained in place by a set collar. The feed pawl 24 is operated both manually and automatically, as will be herein-after described, to rotate the roller 22 and feed the ribbon step by step. Along the 100 right hand edge of the upper run of the ribbon extends a paper guiding and ribbon protecting tape 26 secured at its rear end to a clip 27 attached to the rear bar 19 and having its front end attached to tension springs 28 carried by a tape clip 29 adjustable on the front bar 5 of the track frame. The tape 105 26 carries a top gage 30 which may be riveted in any one of twelve positions longitudinally of the tape to assist in the positioning of the folded forms in any one of twelve positions for the twelve months of the year. Corresponding to this gage on the tape is another gage 31 in the form of a little metal block designed to be used in any one of twelve positions and for this reason carried by a plate 32 finished 110 with the writing surface and having twelve holes for the reception of a screw which retains the block 31 in any desired position. The plate 32 is provided near its ends with slots 33 through which screws are passed 115 into the platen and which permit slight end-wise adjustment of the plate. Disposed alongside of, but not over the right hand edge of the lower run of the ribbon is a second metal tape 34 which, while not neces- 120

sary, is desirable to facilitate the slipping of the ledger sheet under the lower run of the ribbon. The rear end of the tape 34 is secured to the platen by a screw, as shown, and its front end is attached to the upper end of a leaf spring 35 which serves both as a tension device for the tape and a raising device therefor. The spring 35 is passed down through a notch in the front end of the platen and is movable vertically to raise and lower the front end of the tape as the lower run of the ribbon is raised and lowered.

Disposed transversely of the platen adjacent to its front edge is a rock shaft 36 mounted in bearings 37 and having three forwardly extending arms 38, 39 and 40. The arms 38 and 39 are connected to the tracks by a link 41 (accommodated by openings in the platen) to cause the track frame 20 to swing up or down as the shaft 36 is rocked. The arm 40 on the shaft 36 plays between two pins 42 and 43 extending from the upper and lower ends of a slide 44 which carries the spring 35 and is guided in a 25 guide-block 45 depending from the under side of the platen. It is intended that the track frame shall have a normal tendency to rise. This tendency is derived from a spring 46 secured to the platen and to an 30 arm 47 projecting from the shaft 36. When it is desired to lower the track frame to its normal operative position, shown in Fig. 4, this may be done by bearing on its front end with sufficient pressure to overcome the 35 spring 46. I prefer, however, to provide at one side of the track frame a vertically disposed push-rod 48 guided in a bearing 49 and connected to the front end of a comparatively long arm 50 extended from one 40 end of a rock shaft 51, journaled in bearing blocks 52 and provided with a short arm 53 connected by an extensible link 54 with an arm 55 depending from the shaft 36. When the track frame is in elevated position the 45 operator may force down the push-rod 48 thus depressing the arm 50, rocking the shaft 51 and the shaft 36 to cause the arms 38 and 39 to draw down the track frame. The vertical movement of the second tape 34 is materially less than that of the track frame, the interval between the pins 42 and 43 providing considerable lost motion for the arm 40, so that it contacts with these pins near the opposite ends only of its movement and 55 therefore imparts only a slight shifting movement to the slide, 44. When the track frame is depressed it is automatically locked. At one end of the shaft 36 is fixed a locking arm 56 engaging a latch 57 pivoted at its upper end and having its lower end connected by a connecting rod 58 to an arm 59 extended from a transverse rock shaft 60 journaled in bearings 61 and provided at its ends with arms 62 and 63. The 60 arm 63 is connected to the rear end of a push-rod 64 which extends under the platen and projects at the front end thereof. Normally the locking arm 56 is engaged by the latch 57 which locks the rock shaft 36 in proper position to hold the track frame depressed. If, however, it is desired to allow the frame to rise, the operator, by pushing upon the front end of the push-rod 64 rocks the shaft 60 which, through the connecting rod 58, draws the latch 57 from under the 65 locking arm 56 and permits the spring 46 to raise the track frame. The latch 57 is yieldingly held in locking position by a spring 65 attached to the arm 59.

In addition to the push-rod 64, which 80 constitutes manual means for releasing the lock, I provide an automatic release which includes the arm 62 carried by the shaft 60 and provided at its upper end with the pivoted contact piece 66, designed to be engaged 85 by a vertically adjustable contact piece 67 mounted at the rear side of the machine frame. When the machine moves rearwardly the contact piece 67, if in its depressed or operative position, will engage 90 the contact piece 66 and swing the arm 62 to rock the shaft 60 and release the latch 57.

The shaft 60 affords a journal for a lever 68 connected to the lower end of the ribbon feed lever 25 by a connecting rod 69 and 95 having its upper end connected to the rear end of the push-rod 70 extended beyond the front of the platen. The hub of the lever 68 is slotted, as shown, at 71 to engage a pin 72 projecting from the shaft 60. Whenever the shaft 60 is rocked either by the push-rod 64 or by the rearward movement 100 of the machine, the pin 72 will engage one end of the slotted hub of the lever 68 and swing the latter to feed the ribbon. If, after 105 the machine has moved back, it is desired to feed the ribbon any desired distance, this may be done by manipulating the push-rod 70, the slot and pin connection between the lever 68 and the shaft 60 permitting this 110 oscillation of the lever. This ribbon feeding mechanism is provided with a retracting spring 73, which may be connected to one of the rear brackets and to the connecting rod 69 to retract the ribbon feeding pawl 115 after each advance thereof. It will be noted that the push-rod 70 constitutes manually operated ribbon feeding means by which the automatic feed of the ribbon is effected by the act of moving the machine back beyond 120 the printing area.

For the posting of each successive month machine stops are provided to arrest the machine when drawn forward, in successive predetermined monthly positions. These 125 machine stops 74 are in the form of studs projecting laterally from two stop bars 75 extending along opposite sides of the platen and movable laterally on guide rods 76. The stops 74 are screwed into the bar 75 at any 130

one of a series of points determined by a series of threaded openings in the bar and these stops are accommodated by a corresponding series of openings 77 in the side plates on the platen frame. These latter openings are preferably numbered in correspondence with the months of the year. When the machine stops 74 are projected beyond the sides of the platen they are disposed in the paths of stop plates 78 carried by the machine. Inasmuch as the adjustment of different machines is apt to vary, it is preferable to provide the stop plates 78 with stop screws or other forms of adjustable contact pieces for engaging the machine stops. These monthly machine stops are intended to arrest the machine in an initial monthly position and must then be withdrawn to permit the machine to be line spaced in the usual way from line to line of the posting medium. It is to permit this alternate projection and withdrawal of the machine stops that the bars to which they are connected are mounted to move laterally. Disposed longitudinally of the platen is a crank shaft 79 journaled in suitable bearings and having cranks 80, 81 and 82 in the form of disks. The disks 80 and 82 are connected to the adjacent stop bar 75 by short links 83 and the disks 81 and 82 are connected by somewhat longer links 84 with the stop bar 75 at the other side of the platen. To facilitate the manipulation of the shaft 79, the latter is provided at its front end with a thumb wheel 85. Obviously by turning the wheel 85 the stops 74, at opposite sides of the platen, may be withdrawn or projected simultaneously.

Vertically movable in a slot 86 extending transversely of the platen is a top guide or gage plate 87 having at its upper end a clamp 88 designed to clamp the top edge of the ledger sheet and cut away, as shown in Fig. 17, to accommodate the two tapes 26 and 34. In advance of the slot 86 and extending along the inner side of the left hand rail adjacent thereto, the platen is provided with another slot 89 in which is vertically movable a gage plate or abutment 90, the upper edge of which is normally flush with the writing surface. The ends of the plate 87 are guided below the platen in bearing blocks 90^a and said plate rests upon the ends of arms 91 projecting from a shaft 92 having bearings 93 and connected by a clutch 94 to a somewhat shorter shaft 95, which in turn is connected by a clutch 96 with the hub 97 of an arm α connected by a link α' with the short front end of a double cam lever 98. The cam lever 98 projects above the platen and has a cam track 99 which, when engaged by a roller 100 on the machine, causes the swinging of the cam lever to rock the shafts 95 and 92 for the purpose of causing the arms 91 to raise the plate 87.

This occurs when the machine is thrown back from the work and results in raising the clamp 88 away from the platen to release the sheet and presenting the plate 87 as a guide and abutment for the top edge of a new sheet. In addition to the described automatic operating device for the clamp plate 87, manual operating means for said plate are provided. This means consists of a handle 101 extended from the front end of a shaft 102 journaled in bearings 103 and 104 and having an arm 105 which underlies an arm 106 projecting from the shaft 95. It is obvious that by rocking the shaft the arm 105 will raise the arm 106, thus causing the arm 91 to elevate the plate 87. Normally the plate 87 is held depressed by a spring 107 connected to a depending arm 108 of a short shaft 109 journaled in bearings 110 and having an arm 111 extended into an opening in the plate 87. The spring 107 thus serves to retract not only the plate 87 but the shafts 92 and 95 as well.

It is sometimes desirable to disconnect the clamp plate 87 from both the manual and automatic operating devices, to wit, the cam 99 and the handle 101. It is for this purpose that the clutch 94 is provided. To operate this clutch a clutch lever 112 is connected by a connecting rod 113 to a crank 114 at the rear end of a shaft 115, journaled in suitable bearings and provided at its front end with a crank handle 116 having the usual spring plunger 117 which engages one of a pair of openings in a plate 118 to hold the handle in either of two positions to retain the clutch 94 either in or out of action.

The lower edge of the longitudinally disposed abutment and gage plate 90 rests on a pair of arms 119 projecting from a shaft 120 which also has an arm 121 overlying the arm 106. Thus when the arm 106 is operated either from the machine-operated cam 98 or the handle 101, the plate 90 will likewise be raised simultaneously with the raising of the plate 87. The positive retraction or depression of the plate 90 is effected by a spring 122 acting on a bell crank lever 123, one end of which is connected to the spring and the other end of which projects into an opening in the plate 90. This bell crank lever 123 is mounted to rock on a shaft 124 which has a pin 125 engaging a slot in the hub of the lever. This permits the lever to oscillate independently of the shaft as the plate 90 moves up and down. At the end of the shaft 124 a crank handle 126 is provided for the purpose of rocking the shaft 124 a sufficient distance to cause the pin 125 to swing the bell crank lever out of engagement with the plate 90 against the resistance of the spring 122 (see Fig. 3), so that the plate 90 may be lifted out of the slot and a toll bill clamp substituted therefor. The toll bill clamp is substance 128

tially like the plate 90 except that it is provided at its upper edge with a clamping flange similar to that of the plate 87. When the toll bill clamp is employed in lieu of the plate 90, the clutch 94 is in its released position in order to disconnect the transverse plate 87 from the operating devices and inasmuch as the toll billing operation requires the use of neither the plate 87 nor the ribbon, the latter is entirely removed from the machine and provision is made whereby such rearward movement of the machine, as is necessary to remove it from over the toll sheet, effects the automatic 10 operation of the toll clamp but does not effect the release of the track frame. This operative requirement is met by providing the cam 98 with a cam track 127, the effective portion of which lies much nearer the front 15 of the platen than the effective portion or rise of the other cam track 99. The machine frame is equipped with a second roller 128 designed for coaction with the cam track 127 and carried by a pivoted arm 129 which, 20 during the operation of ledger posting, is swung up to the inoperative position shown in Fig. 1. When toll billing is to be done, this roller 128 is swung down to its operative position and then when the machine is 25 moved back, said roller coacts with the track 127 and effects the raising of the toll clamp before the machine has moved back far enough to effect the automatic release of the track frame, which, therefore, remains 30 stationary during the toll billing operation.

It is sometimes desirable to manipulate the clamps manually when the machine is at the rear end of the platen with the cam lever 98 held in its depressed position. Ordinarily, of course, this position of the lever would insure the retention of the clamps in their elevated positions. It is therefore necessary to provide means for releasing the clamps from the cam lever so that said 40 clamps may be operated manually while the lever is held down by the machine. This means includes the clutch 96 which is arranged to be operated by a bell crank lever 130 bifurcated to engage the rear end of the shaft 102 which may be drawn forward longitudinally to shift the bell crank lever and unclutch the shaft 95 from the hub of the cam lever 98 to which one of the clutch members is connected in the manner described. To accommodate as well as to limit the reciprocatory and oscillatory movements of the shaft 102, the rear bearing of the latter is slotted at 103 for the reception of a pin 104 projecting from the shaft and for 50 additional security the shaft may be provided with a set collar in rear of the front bearing. When the clamps are unclutched from the cam lever by pulling the shaft 102 forward and the machine is thrown back 55 to the rear of the platen, the depression of

the cam lever by the machine moves the interfitting members of the clutch out of alignment; therefore, when the shaft 102 is released after it has been used to manipulate one or both of the clamping plates, while 70 the cam lever is held depressed by the machine, the clutch 96 will not reengage. This, however, is not material because as soon as the machine again comes forward the retraction of the cam lever to its normal position will realine the members of the clutch which will snap back into engagement to restore the parts in position for the automatic raising of the clamp plate or plates when the cam lever is again depressed by 80 the rearward movement of the machine.

What I claim is:

1. The combination with a flat platen, of a machine supporting structure mounted to swing relative to the platen, an endless 85 transfer web mounted to swing with said structure, a tension device for said web, means for locking the machine supporting structure in normal position, and means for raising said structure when released. 90

2. The combination with a flat platen, of a machine supporting structure mounted to swing relative thereto, an endless transfer web movable with said structure, tension mechanism for the web, means for holding 95 the machine supporting structure in normal position, means for moving said structure away from the platen when released, and work-engaging means extended along the edge of the transfer web to engage the work. 100

3. The combination with a flat platen, of a swinging machine supporting structure, an endless transfer web carried by and movable with said structure, a swinging tension device inclosed by said web, work-engaging 105 means including a tape extended along the edge of the transfer web, means for locking the machine supporting structure in normal position, means for moving said structure away from normal position when released, 110 and releasing means including manually and automatically operated devices for effecting the release of said machine supporting structure. 115

4. The combination with a flat platen, of a machine supporting structure mounted to swing toward and from the platen, an endless transfer web movable with said structure, tension and feed devices for said web, locking means for the machine supporting 120 structure, and operating mechanism common to the locking means and the web feeding device.

5. The combination with a flat platen, of a plurality of work-engaging devices movable relative thereto, an operating device for said work-engaging devices, and means whereby an operative connection may be established between the operating device and one or both of the work-engaging devices. 130 125

6. The combination with a flat platen, of a pair of work-engaging plates movable relative thereto, an operating device for said plates, and operating connections intermediate of said plates and the operating device, said connections including clutches whereby one, both or neither of said plates may be connected to the operating device.
7. The combination with a flat platen, of 10 a pair of work-engaging plates movable relative thereto, an operating device for said plates, operating connections intermediate of said plates and the operating device, said connections including clutches whereby one, 15 both or neither of said plates may be connected to the operating device and separate operating devices for the clutches.
8. The combination with a flat platen, of 20 longitudinal and transverse work-engaging plates, machine operated means for moving the plates relative to the platen, manual means for operating said plates and means for disconnecting the machine operated means to permit the manual operation of 25 the plates independently thereof.
9. The combination with a flat platen and a swinging machine supporting structure, of a transfer web movable with said structure, vertically movable work-engaging plates arranged to engage the work elements 30 associated with the transfer means, means for holding the machine supporting structure in normal depressed position, a machine operated releasing device for said holding means, and machine operated means for 35 moving the work-engaging plates.
10. The combination with a flat platen and a swinging machine supporting structure, of a transfer web movable with said 40 structure, vertically movable work-engaging plates arranged to engage the work elements associated with the transfer means, means for holding the machine supporting structure in normal depressed position, a machine operated releasing device for said holding 45 means, and machine operated means for moving the work-engaging plates.
11. The combination with a flat platen, of a writing machine movable thereover, of 50 adjustable and retractile machine stops located on opposite sides of the platen to arrest the machine in predetermined positions, machine operated work-engaging devices for retaining a ledger sheet in a predetermined position, a tape arranged to engage the fold or bight of a bill sheet and gage devices carried by the platen and tape respectively to position the bill sheet at successive 55 positions in which the machine is arrested by the machine stops, the machine operated work-engaging devices for the ledger sheet being disposed longitudinally and transversely of the platen.
12. The combination with a flat platen, of a plurality of work engaging devices movable relative thereto, operating mechanism for said work engaging devices, and means controlling the operative relation between the said operating mechanism and one of 70 said work engaging devices.
13. The combination with a flat platen, of a plurality of work engaging devices movable relative thereto, of operating mechanism, and means controlling the connection 75 of said operating mechanism with the respective work engaging devices.
14. The combination with a flat platen, of a plurality of work engaging devices movable relative thereto, an operating device 80 common to the work engaging devices, and clutches controlling the operative relation between the operating device and the work engaging devices.
15. The combination with a flat platen, of a work holding structure movable toward and from the platen, means for holding said structure in normal position, a machine operated releasing device for said holding means, a work engaging device, and machine operated means for moving said work 85 engaging device.
16. The combination with a flat platen, of a machine supporting structure mounted to swing relative to the platen, an endless 90 transfer web mounted to swing with the said structure and having upper and lower runs both located above the platen, a tension device for said web, means for locking the machine supporting structure in normal position, and means for raising said structure 95 when released.
17. The combination with a flat platen, of a machine supporting structure mounted to swing relative thereto, an endless 100 transfer web movable with said structure and having both its upper and lower runs located above the platen, tension mechanism for the web, means for holding the machine supporting structure in normal position 105 with the runs of the web disposed closely adjacent to each other and to the platen, means for moving the said structure away from the platen when released and work engaging means associated with the web.
18. The combination with a flat platen, of a swinging machine supporting structure, an endless transfer web carried by and movable with said structure and having both of its runs located above the platen, a 110 swinging tension device inclosed by said web, work engaging means including a tape extended along the edge of the transfer web, means for locking the machine supporting structure in normal position, means for 115

moving said structure away from normal position when released and releasing means including manually and automatically operated devices for effecting the release of said machine supporting structure.

19. The combination with a flat platen, of an endless transfer web having its upper and lower runs located thereover and disposed closely adjacent to each other and to

the platen, and means for effecting relative 10 movement of the runs to dispose the same in separated relation.

In testimony whereof I affix my signature in presence of two witnesses.

EDWIN NAPIER STEPHENSON.
